UNITED STATES PATENT OFFICE.

JOHN ALLEN HOLMES, OF SALT LAKE CITY, UTAH, AND JOHN F. WOOD, OF DENVER, COLORADO.

CONCENTRATOR.

SPECIFICATION forming part of Letters Patent No. 709,770, dated September 23, 1902.

Application filed October 2, 1901. Serial No. 77,288. (No model.)

To all whom it may concern:

Be it known that we, JOHN ALLEN HOLMES, of Salt Lake City, in the county of Salt Lake and State of Utah, and JOHN F. WOOD, of Denver, in the county of Arapahoe and State of Colorado, citizens of the United States, have invented a new and Improved Concentrator, of which the following is a full, clear, and exact description.

This invention relates to improvements in concentrators and amalgamators; and the object is to provide a machine of this character by means of which all the gold or other values may be quickly separated from the ore or pulp placed therein.

We will describe a concentrator embodying our invention and then point out the novel features in the appended claims.

Reference is to be had to the accompanying drawings, forming a part of this specification, in which similar characters of reference indicate corresponding parts in all the figures.

Figure 1 is a right-hand side elevation of a machine embodying our invention. Fig. 2 is a left-hand side elevation. Fig. 3 is a front end view. Fig. 4 is a rear end view. Fig. 5 is a longitudinal section on the line 5 5 in Fig. 6. Fig. 6 is a section on the line 6 6 of Fig. 5. Fig. 7 is a section on the line 7 7 of Fig. 5. Fig. 8 shows one side of the machine and also the arrangement of ports through which the gold or values are discharged from one pan into another and thence out of the machine. Fig. 9 is a plan view showing a means for moving the sluice-box laterally. Fig. 10 is a section on the line 10 10 of Fig. 13, showing a system of levers for imparting the side movements to the sluice. Fig. 11 is a plan view thereof. Fig. 12 is a section on the line 12 12 of Fig. 11, and Fig. 13 is a section on the line 13 13 of Figs. 10 and 12.

The sluice-box comprises side boards 25 26, arranged on a reservoir 27 and adapted to have both a longitudinal and a transverse movement on said reservoir, as will be hereinafter explained.

Supported on a frame 27^a at the front end of the machine is a series of hoppers 28, and a feed-trough 29 is also supported by the frame and is common to all the hoppers. This feed-trough 29 has a sieve material 30 in its

upper portion, and said feed-trough communicates with the several hoppers through a throat 31, and extended over the upper end of each hopper is a sieve material 32, upon which is placed a filter material 33. It will be noted that the outer walls of the end hoppers 28 extend upward, as at 34, into boxes 35 36, adapted to receive water flowing over these extensions 34 to supply the water to the pans 60 or launders. Attached to the lower end of each hopper is a pan 37, having a port 38, adapted at certain times to communicate with a port 39 in a swinging valve-plate 40. Rotary valve-plates 41 are placed upon the bottom of the pans 37, and these rotary valve-plates 41 are provided with ports 42, adapted to come into register with the ports 38, and extended upward on each valve-plate 41 are fingers 43, which serve as agitators for the pulp in the hoppers. Extended upward from each rotary valve-plate 41 is a shaft 44, the upper ends of the several shafts being provided with bevel-gears 45, meshing with bevel-gears 46 on a driving-shaft 47, to which a pulley 48 is attached. This pulley 48 is here shown in the form of a cone-pulley, so that a greater or less speed may be imparted to the shaft 47, as desired. The swinging valve-plates 40 are adjustable to more or less close 80 the ports 38 to regulate the discharge of material to the machine. For the purpose of adjusting said plates we provide each one with an adjusting-rod 49, which extends outward to one side of the machine through a plate 50, 85 and on the outer end of each rod, which is screw-threaded, is an adjusting-nut 51. The adjusting-rods 49 have pivotal connection with the valve-plates, as indicated at 52.

Arranged longitudinally in the sluice-box 90 and one above the other are sluice-pans 53, 54, 55, and 56. These several pans are longitudinally curved, and they are also inclined from one side of the machine to the other, the highest point being at the side where the gangue is discharged, the lower portion of course being at the side where the values discharge. In one side of the sluice-box are formed the outlets for the gangue discharging from the several pans. These outlets are indicated at 57 for the pan 53, 58 for the pan 54, 59 for the pan 55, and 60 for the pan 56.

These outlets are elongated and are somewhat above the edge of the pans, the purpose of which will be hereinafter mentioned. In the opposite side board of the sluice-box are 5 the discharge-ports 61, 62, and 63 for the several pans, and also at this side is a port 64, through which material passes from the pan 53 to the pan 54, a port 65, through which material passes from the pan 54 to the pan 55, and 10 a port 66, through which material passes from the pan 55 onto the pan 56. (See Fig. 8.) The ports 61, 62, and 63 are regulated by means of valves 67, each one of which has a stem 68, (see Figs. 1, 2, and 6,) passing upward at the outer side of the sluice-box and having its upper threaded end extended through a bracket 69, and adjusting-nuts 70 and 71 engage with the threaded portions of the stems. Water is discharged from the 15 box 35 onto the pans 54, 55, and 56 through a pipe 72, with which flexible connections 73 engage, these several flexible pipes 73 terminating in nozzles 74, discharging onto the said pans. (See Fig. 5.) These flexible pipe- 20 sections 73 permit of the shaking movements of the sluice-box, and the water passing therethrough may be controlled by a valve 75. Water is also discharged from the box 35 onto a distributing-pan 76, arranged on 25 the sluice-box above the pan 53. A perforated pipe 77 extends over the highest portion of this inclined distributing-pan and has a flexible pipe connection 78 with a valved pipe 79, leading from the box 35.

30 It is thought that other details of construction of the machine may be more clearly brought out by a description of the operation, as follows: When the ore or pulp from stamps or other pulverizing machinery is dumped 35 into the feed-trough 29, the material, which contains a certain amount of water, fills the several hoppers 28, and a certain amount of water is separated from the pulp as said water passes out through the screen material 40 at the upper end of the hoppers and thence through the filter material 33. The water passing through said filter material flows over the dams or projected upper ends 34 of the end hoppers into the boxes 35 and 36, and the 45 water from the box 35, as before described, passes onto the several pans in a practically clear condition. The particles of ore, coarse and fine, fall to the bottom of the hoppers, and when the rotary valves 41 are set in motion 50 said ore is agitated and broken up, and as the ports 42 come in line with the ports 38 and 39 a certain amount of ore or pulp is discharged onto the pan 53. This amount, of course, can be regulated by adjusting the 55 valves 40. The ore or pulp thus discharged onto the pan is of plastic consistency, and it is carried by the movements of the machine, which, as will be hereinafter described, will give a whirling motion to the ore, and as the 60 ore or pulp travels down the incline of the said pan 53 and passes under the water-distributing pan 76 an even distribution of the

ore is insured, as the said pan 76 serves to keep the particles of mineral near the bottom of the pan 53. The coarse granulations of 65 gangue are forced to the surface and discharged at the port 57, assisted by a certain amount of water from the pan 76, and this material flows into launders 80 and 81. The particles of mineral and the finer granulations of ore or pulp pass out of the valved port 61 into a launder 82, which forms by its particular construction a 'seal against the valve for said port 61. As indicated by the arrow in Fig. 8, the material then passes 70 through the port 64 onto the pan 54, where it is agitated as before, the heavier particles of gangue contained therein moving to the higher portion of the pan and discharging through the port 58 into the launder 81. The 75 particles of mineral and finer granulations of ore passing out at the valve-opening 62 pass into a launder 83 and thence pass through the port 65 onto the plate 55, where they are treated as before, the gangue from this pan 80 85 discharging through the port 59 into a launder 84 and thence to a launder 85. The mineral separated in the pan 55 passes out through the port 63 into a launder 86, thence through the port 66 into a pan 87, arranged 90 below the several other pans and inclined in a similar manner and where the pulp containing mineral receives treatment as in the former pans. The water-supply for the pan 87 is obtained through a pipe in the manner 95 described for the other pans. The gangue is discharged at 60 into the launder 85, while the mineral passes out through a port 88, controlled by a valve 89, operated in a similar manner to the other port-valves. From the 100 pan 87 the mineral discharges into a receiving-pan 90, which is located in a compartment 91 of the reservoir 27. It may be here stated that this receiving-pan 90 is submerged 105 in water contained in the tank, and the depth 110 of this water may be regulated by an overflow-pipe 92. As the material passes over the edge of the receiving-pan 90 it falls upon an inclined amalgamated plate 93, supported on a frame 94 within the section 91 of the 115 reservoir 27. From this plate the material passes over a trough 95, supported by said frame. This trough is provided as a holder for mercury, and from this trough the material passes into the compartment 91 of the 120 reservoir. The material collected in the 125 launders 80 and 81 discharges through a port 96 onto a pan 97, and the gangue discharged from the launders 84 and 85 passes through a port 98 onto said pan 97. It will therefore be seen that the discharge from the 130 several pans is collected and re-treated in the pan 97, and particles of mineral that escape from the preceding pans are secured and discharged at a valved aperture controlled by a valve 99, and from this valve-controlled opening the material discharges into a receiving-pan 100, which is submerged 135 in the water contained in the section 101 of

the reservoir 27, the depth of the water being regulated by an overflow-pipe 102. From the receiving-pan 100 the material flows or falls upon an amalgamated plate 103, supported in an inclined position by means of a frame 104 in the tank, and which also supports a mercury-trough 105, over which the material from the plate 103 passes. The accumulation of concentrates in the sections 91 and 101 of the reservoir 27, with the water received from the pans 87 and 97, causes the water to rise and overflow through the pipes 92 and 102, into a separator 106, attached to one side of the reservoir 27. The material 15 passes into said separator beneath a screen 107, upon which is a filtering material 108 of a depth to permit the free outlet of water over the side walls 109 of said separator into a waste-pipe 110. Water is supplied to the 20 gangue-receiving launder 85 by means of a pipe 111, leading from the water-box 36.

It will be observed that the fine particles of mineral are kept under water and prevented from rising to the surface from the beginning 25 to the finishing of the operation. The outlet 92 of the section 91 of the reservoir 27 is such a distance from the inlet-pan 87 that the circulation of water is very slow, and should any particles of mineral get into the pipe 92 30 and thence into the separator 106 they are prevented from escaping by the filtering material 108 and may be drawn off through the valve-controlled pipe connecting with said separator. It will be further observed that 35 any particles of mineral that pass with the gangue from the several pans are reworked in the pan 97 and pass into the compartment 101 of the tank, as before described, producing a certain grade of concentrates, the gangue 40 passing off over an apron 112 at the feed end of the machine. At the point where this apron 112 is located the bottom of the pan is provided with a longitudinal channel 113, into which a pivot-pin 114, attached to one end of 45 the reservoir 27, passes. This pin 114 forms the pivot on which the sluice-box may swing and also upon which it may move longitudinally.

Longitudinal reciprocating motion is given 50 to the machine by means of a pitman 115, having pivotal connection at one end with the sluice-box and at the opposite end with a crank-pin 116, adjustable radially in a slot formed in a crank-disk 117, mounted on a 55 shaft 118, to the outer end of which a cone-pulley 119 is attached and also a hand-wheel 120.

As a means for imparting lateral movements to the sluice-box we employ a system 60 of levers. (Best understood by reference to Figs. 9 to 13.) This mechanism comprises a boxing 121, an upper arm 122, arranged at the top, and a lower arm 123, the said arms being arranged at right angles to each other. The lower arm 123 is longitudinally slotted to receive a stud and clamping devices 124, attached to a block 125, which has a pin 126 engaging in a slot formed longitudinally in a

lever 127, pivoted on a bracket 128, attached to the reservoir 27. A lever 129 is pivoted to a bracket 130, attached to the sluice-box, 70 and the opposite end of this lever 129 is provided with a slot 131, and a pin 132, extended from the lever 127, passes into said slot 131. This pin engages in a block 133, adapted to slide in said slot, and with this block 133 75 an adjusting-screw 134 engages, the said adjusting-screw operating in a tapped hole in an end wall of the slot 131. A longitudinally-slotted bracket 135 is attached to the sluice-box, and a pin 136 on the lever 122 80 passes into said slot. Therefore as the sluice-box is moved back and forth lengthwise the lever 122 will be rocked back and forth, causing the arm or lever 129 to impart a transverse reciprocating motion to the sluice-box. 85 The amount of movement may be regulated by means of the block 125 and clamping device 124, pin 126 engaging lever 127 and the pin 132 engaging the box 133 in the slot in the lever 129. When there is no transverse 90 motion required, by placing the block 125 in position as shown in Figs. 11 and 13 and releasing the adjusting-screw 134 the machine is thereby allowed to travel longitudinally in a straight line. 95

Having thus described our invention, we claim as new and desire to secure by Letters Patent—

1. A concentrator, comprising a sluice-box, a series of pans arranged one above another 100 in the sluice-box, the said pans being longitudinally curved and laterally inclined, the said sluice-box having openings for discharge of gangue at the higher sides of the pans, and openings at the lower sides of the pans for 105 discharge of values, launders arranged one within another and receiving material from the first-named openings and means for imparting a reciprocating motion both laterally and longitudinally to the sluice-box carrying 110 the pans, substantially as specified.

2. An ore-concentrator, comprising a sluice-box, a series of pans arranged one above another in the sluice-box, the said pans being longitudinally curved and arranged to discharge at one side from one pan to another intermediate of the ends, launders at the opposite sides in which material is discharged from the pans, means for imparting a longitudinal reciprocating motion to the sluice-box, and means comprising a shaft and a plurality of levers for imparting a transverse reciprocating motion to the sluice-box, substantially as specified. 115

3. An ore-concentrator, comprising a sluice-box, a series of pans arranged one above another in said box, the said pans being longitudinally curved and inclined laterally, valve-controlled outlets at the lower sides of the pans, launders for receiving material from 125 said outlets and adapted to discharge into the pans consecutively from the second pan to the lowermost one, the said launders being arranged one within another, and launders 130

at the opposite side for receiving the gangue from the pulp, substantially as specified.

4. An ore-concentrator, comprising a sluice-box mounted to reciprocate, a series of longitudinally-curved pans arranged one above another in vertical alinement in the sluice-box and adapted to discharge material from one pan to another, means for discharging water upon the pans one independently of another, a divided tank on which the box is supported, and amalgamating devices in the tank, substantially as specified.

5. An ore-concentrator, comprising a sluice-box, pans arranged therein one above another, a series of hoppers arranged above the feed end of the sluice-box, a feed-trough common to all the hoppers, a valve for the outlet of each hopper, an agitator carried by each valve, a sieve material at the top of each hopper, and a filter material on the sieve material, substantially as specified.

6. An ore-concentrator, comprising a sluice-box, means for imparting reciprocating longitudinal movement to the sluice-box, a series of longitudinally-curved pans arranged in the box one above another, a series of hoppers arranged above the feed end of the sluice-box and having outlet-ports through the bottoms, valves for regulating said outlet-ports, means for operating said regulating-valves, rotary valves for opening and closing said ports, means for simultaneously operating all of said rotary valves, and agitators carried by said rotary valves, substantially as specified.

35 7. An ore-concentrator, comprising a sluice-box, means for imparting reciprocating motion to said sluice-box, a series of pans arranged one above another in said box, a series of hoppers arranged above the feed end of the sluice-box, each hopper having a discharge-opening in its bottom, a valve for regulating the opening in said port, rotary valves in the hoppers and having ports adapted to move into register with the ports in the bottom of the hoppers, shafts extended upward from said rotary valves, a driving-shaft, and gear connections between said driving-shaft and the valve-shafts, substantially as specified.

50 8. An ore-concentrator, comprising a sluice-box, a series of pans arranged one above another in said box, a series of hoppers placed above the feed end of said sluice-box, means for opening and closing discharge-openings through the bottoms of said hoppers, a filter material arranged in the upper portion of the hoppers, water-boxes for receiving water passing through the filter material, and means for conveying water from one of said boxes to the pans, substantially as specified.

55 60 9. An ore-concentrator, comprising a sluice-box, means for imparting a longitudinal reciprocating motion to said box, a series of pans arranged in said box one above another, the said pans being longitudinally curved and inclined laterally, discharge-openings through a side wall of the box at the highest side of the pans, discharge and inlet openings at the

opposite side of the box, a reservoir upon which the box moves, receiving-pans carried by the box and adapted to be submerged in the water contained in said reservoir, inclined amalgamated plates for receiving material from said receiving-pans, the said plates being arranged in the reservoir, and mercury-troughs supported below said plates, substantially as specified.

70 10. An ore-concentrator, comprising a sluice-box, means for imparting a longitudinal reciprocating motion to said box, means for imparting a transverse reciprocating motion to said box, a tank on which the box moves and into which the values finally discharge from the pans, longitudinally-curved pans arranged one above another in the box, means for supplying pulp to the uppermost pan, a water-distributing pan extended over the uppermost pan, and a perforated pipe for discharging water onto said water-pan, substantially as specified.

80 11. An ore-concentrator, comprising a sluice-box, having both a longitudinal and a transverse motion, a series of longitudinally-curved pans arranged one above another in said box and adapted to discharge material at one side one upon another and to discharge gangue at the opposite side, means for discharging water upon the several pans, a reservoir upon which the sluice-box moves, the said reservoir being divided into two compartments, inclined amalgamated plates arranged in the compartments of the reservoir and adapted to receive values from the pans, overflow-pipes for the compartments, a separator for receiving the overflow, a sieve material in the upper portion of the separator, and a filter on said sieve material, substantially as specified.

90 12. An ore-concentrator, comprising a sluice-box, means for imparting reciprocating motion to said sluice-box, a series of pans arranged one above another in said box, the said pans being longitudinally curved and inclined transversely, the sluice-box having discharge-openings and inlet-openings at one side, valves for the outlet-openings, means for adjusting the valves, and launders arranged one within another for receiving material from the higher sides of the pans, said material discharging through openings in a side of the box, substantially as specified.

100 13. An ore-concentrator, comprising a sluice-box, means for imparting motion to said sluice-box, a series of pans arranged one above another in said box, the said pans being longitudinally curved and inclined transversely, launders arranged on the sluice-box one within another and adapted to receive material from the pans at the higher side, and launders at the opposite side of the sluice-box and adapted to receive values from the lower sides of the pans and to discharge material received from one pan to the next lower pan, substantially as specified.

110 14. In a concentrator, a sluice-box, means

for imparting longitudinal reciprocating motion to said sluice-box, means for imparting transverse reciprocating motion to said box, a series of pans arranged one above another in the box, a reservoir on which the sluice-box is mounted to move, said reservoir being divided into two compartments, launders for receiving material discharged from one side of the pans, a pipe for discharging water into said launders, launders at the opposite side for receiving values from the pans, and amalgamated plates arranged in the compartments of the reservoir for receiving values from the lowermost pans, substantially as specified.

15 15. An ore - concentrator, comprising a sluice-box, means for imparting motion to said sluice-box, a series of pans arranged one above another in said box, a series of feed-hoppers arranged above the feed end of the box, valves 20 in the hopper and carrying agitators, water-receiving troughs for receiving water discharged over the upwardly-extended wall portion of the end hoppers, and means for conveying water from said boxes to the machine, 25 substantially as specified.

16. An ore - concentrator, comprising a sluice-box, a series of pans arranged one above another in said sluice-box, the said pans being longitudinally curved and inclined trans-

versely, means for directing water to the pans, 30 a series of hoppers, a feed-trough common to all the hoppers and having a sieve in its upper portion, means for controlling the discharge of pulp from said hoppers onto the uppermost pan, a filter in each hopper, and a receiver for water passing through said filters, 35 substantially as specified.

17. An ore-concentrator, comprising a reservoir, a sluice-box mounted on the reservoir, means for imparting a longitudinal reciprocating motion to the box, and means for imparting lateral movement to the box, comprising a shaft, a sliding connection between said shaft and the box, a lever connection between the lower portion of the shaft and the box, 40 an arm extended from the lower portion of the shaft and having pivotal connection with a fixed support, and a slotted arm above the first-named arm, substantially as specified.

In testimony whereof we have signed our 50 names to this specification in the presence of two subscribing witnesses.
